LEG BRACE

Filed Jan. 23, 1931

Frank A. Danner,
Frank S. Allernau. Attorney

UNITED STATES PATENT OFFICE

FRANK A. DRESSER, OF BURLINGTON, VERMONT

LEG BRACE

Application filed January 23, 1931. Serial No. 510,812.

This invention relates to leg braces or the like, and particularly to a lock for the joint of such a brace.

It is an object of this invention to produce a brace having reinforcing or overlapping joint members effective to prevent lateral motion, whether in an open or closed position.

It is a further object of the invention to provide a joint of the character indicated which will eliminate wear from the upright and the rivet.

It is a still further object of the invention to provide a joint having parts which can be produced by the ordinary stamping processes and this results in cheapness of construction.

It is furthermore an object to provide a lock joint in which the operating parts, such as the spring, are in a protected position on the posterior side of the brace, and to produce a joint which can be covered or provided with a shield to prevent wear on the clothing.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which—

Figure 1 illustrates a view in elevation of one side of a brace, with a lock joint member embodying the invention;

Figure 2 illustrates an enlarged detailed view showing the joint broken;

Figure 3 illustrates a view in front elevation of the brace at the joint;

Figure 4 illustrates a perspective view of one of the elements; and

Figure 5 illustrates a sectional view of the joint on the line 5—5 of Fig. 3.

In these drawings 10 denotes the upper brace member and 11 a lower brace member, each of which is reduced in width and shaped at their meeting ends to form overlapping extensions 12 and 13, respectively, and they are apertured to receive the pivot 14 which also extends through the reinforcing plates 15 and 16 secured to the sides of and project-

ing from the ends of the brace members 10 and 11, respectively.

A reinforcing plate 17 is secured to the inner side of the member 10 and it overlies the outer surface of the extension of the lower member and it is secured on the inner surface of the upper member by fastenings 18, such as rivets or the like, which extend through the outer reinforcing plate 15.

A plate 19 is secured to the lower member 11 by fastenings 20, such as rivets or the like, and the said plate 19 is secured on the pivot 14, and the upper member oscillates on the said pivot. The plate 19 extends above the pivot and lies against the reinforcing plate 17.

The plate 19 has a curved upper end 21 that acts as a cam during the movement of the upper brace member on the pivot. Plates 22 and 23 are secured to the side of the member 10 above the pivot, and the lower edge is shaped to the contour of the camming edge 21 of the plate 19, which plate 19 has its outer surface alining with the outer surface of the plate 23 in order that a locking sleeve 24 may slide freely on the plates 15 and 23 and pass the joint between the upper end of the plate 19 and the plates 22 and 23, it being obvious that when the sleeve embraces those parts of the device immediately above the pivot 14, its engagement with the plate 19 will prevent oscillative movement of the members 10 and 11 with relation to each other.

In other words, the joint will be locked against movement by reason of the said assembled parts.

A spring 25 is connected to the sleeve in any appropriate way, one means for accomplishing the result being shown at 26, and the said spring has its other end connected in appropriate way, as by the apertured lug 27, to the lower brace member, and the relation of parts is such that the spring exerts a pull on the sleeve, tending to hold it in its operative position, as shown in Figure 1. A strap or other device 28 is connected to the sleeve and it may extend upwardly and be attached to a leg band 29 where it will be readily accessible to be pulled upwardly to displace the sleeve from its operative position to the position shown in dotted lines, Fig. 2, which

will permit the joint to be broken and the upper member may then swing on the pivot. The spring will retain the parts in the positions in which they are shown in Fig. 2 and 5 when the brace members 10 and 11 are returned to operative positions or in approximate alinement with each other, the camming end of the plate 19 will displace the sleeve upwardly, permitting the parts to resume 10 their normal operative position and, of course, the spring is relied upon to replace the sleeve in engagement with the plate in substantially the relation which it occupies as shown in Fig. 3. This will serve to again 15 lock the joint against being broken until a repetition of the manipulation, to which reference has been made.

I claim:

1. In a leg brace, upper and lower members, means for pivotally connecting the said members, a plate secured to the lower member and having an aperture in which the pivot is seated, a plate on the upper member overlapping the first mentioned plate and having an aperture to receive the said pivot, a plate secured to the opposite side of the lower member and having an aperture to receive the pivot, the said plate overlapping a portion of the other member and adapted to move with 25 relation thereto, a sleeve embracing and slid- 30 able on the upper member and adapted to engage and disengage the said last mentioned plate and hold the members locked together, a spring anchored to the first mentioned plate 35 and to the sleeve operative to return and hold the sleeve in operative relation with the member and overlapping plate, the said overlapping plate having a camming end adapted to displace the sleeve against the action of the 40 spring for causing the said sleeve to clear the end of the plate as the members are articulated.

2. In a leg brace, upper and lower members, means for pivotally connecting the said members, a plate secured to the lower member and having an aperture in which the pivot is seated, a plate on the upper member overlapping the first mentioned plate and having an aperture to receive the said pivot, a plate 45 secured to the opposite side of the lower member and having an aperture to receive the pivot, the said plate overlapping a portion of the other member and adapted to move with relation thereto, a sleeve embracing and 50 slid- 55 able on the upper member and adapted to engage and disengage the said last mentioned plate and hold the members locked together, a spring anchored to the first mentioned plate and to the sleeve operative to 60 return and hold the sleeve in operative relation with the member and overlapping plate, the said overlapping plate having a camming end adapted to displace the sleeve against the action of the spring for causing 65 the said sleeve to clear the end of the plate

as the members are articulated, and means connected to the sleeve for displacing the said sleeve from operative position and to move it against the action of the aforesaid spring.
